ADJUSTABLE WINDOW CASING

Fred Cervellone, New York, N. Y.

Application October 30, 1946; Serial No. 706,701

1 Claim. (Cl. 20—53)

1

This invention is an improvement in window construction, especially windows having movably mounted sashes to be opened and closed and manipulated for cleaning.

An important object of this invention is to provide a window casing with sashes which can be opened and closed at will, and are so disposed that they can be easily adjusted for cleaning, in a way that permits them to be washed and wiped from the interior of the building or apartment equipped with such windows, and does not require the operator even to lean over the sill to reach the outer surfaces of the panes of glass carried by the sashes.

Another object is to provide a window construction of simple design and inexpensive to produce with relatively few parts in a light and strong assembly that can be readily handled and is most unlikely to get out of order.

The nature and advantages of the invention are made clear in the following description and the novel features are pointed out in the appended claim. But this disclosure is illustrative only and variations in details of form, size and arrangement of the constituent members can be adapted without omitting any of the essential characteristics of the device.

On the drawings,

Figure 1 is a front elevation of a window incorporating the invention.

Figure 2 is a section on line 2—2 of Figure 1.

Figure 3 is a section on line 3—3 of Figure 1.

Figure 4 is a vertical sectional detail showing on a large scale the construction at the lower end of Figure 2.

The window construction includes a frame or casing 1 which has a top 2, sides 3 and a bottom 4. The sides are connected at their midpoints by a horizontal cross bar 5. This casing is set to fill an opening in a wall W, and the sides 3 and the lower faces of the top 2 and cross piece 5 have shoulders 6 which face to the inside of the wall in which the window casing is mounted. In this casing are an upper sash frame 7 between the top 2 and the cross piece 5; and a lower sash frame 8 between the piece 5 and bottom 4, both of which are hinged respectively to the piece 5 and the bottom 4 and can be secured in position to occupy and fill the space enclosed by the frame 1. Each of the frames 7 and 8 has a vertical bar or rail 9 dividing the frames into equal halves, one at each side thereof.

The space in each frame at both sides of the bar 9 receives a framed window pane of glass 10, hinged as indicated at 11 to opposite sides of

2

the frame, and bearing a catch 12 to engage a plate 13 on the bar 9 to hold the framed glass panes in closed position. The inner edges of the sides and top of the frames 7 and 8 and both edges of the vertical bar 9 have shoulders 14 facing outward for the framed glass panes 10 to engage along their sides when the panes are shut. Similar shoulders may be formed along the bottoms of the frames 7 and 8, or any other means to make the framed panes 10 fit snugly and prevent drafts of air may be used. When the catches 12 are released, the framed glass panes can be swung outward and opened. The shoulders 14 on the bars 9 are farther out and are engaged by vertical ribs 15 on the free edges of the frames for the panes 10.

The hinges for connecting the frames 7 and 8 along their bottoms to the casing 1 are shown at 16, along the inner edges of the bottom 4 and cross piece 5. This bottom 4 and the top of the piece 5 have shoulders 17 facing outward, and the outer edges of the lower bars of the frames 7 and 8 have projections or ribs 18 that form shoulders facing inward. The shoulders 18 overlap the shoulders 17 and, with the shoulders 6, make the window tight all around the frames 7 and 8.

When the frames 7 and 8 are closed, they are held in that position by catches 19 at the tops engaging the upper part 2 and piece 5 of the casing 1. Both of these frames can be adjusted for cleaning the outer faces of the framed panes 10 by undoing the catches 19 and swinging the frames 7 and 8 inward and downward along their lower edges, by reason of the hinges 16 connecting them to the casing 1. In that position, the cleaner can reach the glass from the inside of the apartment and does not have to be on the outside of the building or even lean out of the window. The piece 5 has projections 20 on which the upper frame 7 rests when lowered inward; and the lower frame 8 is connected to the frame 1 at each side by a pair of links 21 with straight sides, pinned to the sides of this frame and the sides 3, which have recesses 22 for clearance, and to each other to limit the downward and inward movement of the frame 8. The framed glass is omitted from the lower part of Figure 2 for convenience, only the hinges 11 being shown in that figure.

This construction makes a tight window frame which is sealed against the outside air and weather by the engagement of the frames 7 and 8 with the shoulders 6 and 17 of the casing 1, and the engagement of the framed glass 10 with the shoul-

ders 14 in the frames 7 and 8. The framed glass can be opened and closed at any time; and either the upper or lower frame 7 and 8 can be swung inward to open the window for cleaning the outside of the glass. The construction is especially desirable for upper story windows because it eliminates the risk of the cleaner falling, and at the same time the window serves perfectly all the intended purposes of said window.

The invention thus is a very practical device, 10 inexpensive to manufacture and easy to mount and operate, and is well calculated to give all of the advantages for which the invention was made. Of course any suitable materials, such as wood, metal, plastic or other substances can be employed 15 in the construction of the window.

Having described my invention, what I believe to be new is:

A window construction comprising a casing comprising a top, a bottom and sides, a cross piece uniting the midpoints of the sides, a sash frame hinged at its lower edge to the bottom and a frame hinged at its lower edge to the cross piece, said frames filling the spaces between the cross piece and the top and bottom, releasable catches 20 to connect the tops of said frames to said casing, the sides, top and lower side of the cross piece having inward facing shoulders engaged by the

frames, the bottom and upper side of the cross piece having outward facing shoulders, the lower ends of said frames having ribs along their edges projecting downward to cover the last-named shoulders, each of said frames having a vertical bar joining the top and bottom at the middle, said frames and said bar having outward facing shoulders, framed window panes hinged to the opposite sides of the frames and engaging said shoulders, catches for said framed panes to engage the vertical bar thereof; and means for limiting the inward and downward movement of the sash frames in said casing.
